(57) **CLAIM**

The ornamental design for the pedal for trash can assembly, as shown and described.

DESCRIPTION

FIG. 1 is a perspective view for a pedal for trash can assembly showing my new design;

FIG. 2 is a top plan view of the pedal;

FIG. 3 is a front plan view of the pedal;

FIG. 4 is a bottom plan view of the pedal;

FIG. 5 shows a left side plan view of the pedal; and,

FIG. 6 shows a right side plan view of the pedal.

The surface(s) or portion(s) of the article not shown in the drawing or described in the specification form(s) no part of the claimed design.
